UNITED STATES PATENT OFFICE.

EMIL WESTMAN, OF MINNEAPOLIS, MINNESOTA, ASSIGNOR TO THE ENTERPRISE MACHINE COMPANY, OF SAME PLACE, (PARTNERSHIP COMPOSED OF WILLIAM KAMPFF AND N. G. SAMPSON.)

FEED-CUP FOR EXPLOSIVE-ENGINES.

SPECIFICATION forming part of Letters Patent No. 681,382, dated August 27, 1901.

Application filed November 2, 1900. Serial No. 35,208. (No model.)

To all whom it may concern:

Be it known that I, EMIL WESTMAN, a citizen of the United States, residing at Minneapolis, in the county of Hennepin and State 5 of Minnesota, have invented certain new and useful Improvements in Feed-Cups for Explosive-Engines; and I do hereby declare the following to be a full, clear, and exact description of the invention, such as will enable others skilled in the art to which it appertains to 10 make and use the same.

My invention has for its object to provide an improved feed-cup for explosive-engines.

To this end my invention consists of the 15 novel devices and combinations of devices hereinafter described, and defined in the claims.

The invention is illustrated in the accompanying drawings, wherein like notations refer to like parts throughout the several views.

In said drawings, Figure 1 is a view, partly in elevation and partly in section, with some portions broken away, illustrating my improved feed-cup as applied in working position. Fig. 2 shows the feed-cup detached in vertical section on the line $x^6 x^6$ of Fig. 1. Fig. 3 is a view of the cup in horizontal section on the line $x^7 x^7$ of Fig. 2; and Fig. 4 is a view showing the feed-cup, partly in elevation 25 and partly in section, on line $x^8 x^8$ of Fig. 3.

The valve-chest 2 is attached to the cylinder-casting 3 in the customary or any suitable way. The valve-chest 2 is tapped by an exhaust-pipe 21. The intake-valve 8 of the 35 engine is seated in the branch 22^a of a suitable casing, the other branch of which is marked 22^b. This valve-casing 22^a 22^b is detachably secured to the valve-chest 2 and is suitably recessed to afford the commingling-40 chamber for the explosive mixture, which is drawn into the engine under the suction-stroke of the piston. The part 22^b of the valve-casing projects at right angles from the part 22^a of the casing, as clearly shown in Fig. 1, and is tapped by the air-supply pipe 23 and the feed-cup 24, which will now be described in detail.

The feed-cup 24 is preferably formed with a glass body c and metallic ends c^1 c^2 . The

bottom end c^1 is preferably made in the form 50 of a casting, having formed integral therewith an inlet-pipe section c^3 , tapped by the oil-supply pipe 25, leading from the pump or other source, a discharge-head c^4 , having formed therein a passage c^5 for delivering 55 the oil from the feed-cup to the commingling-chamber of the engine, an overflow-pipe section c^6 , tapped by a return-pipe 26, leading back to the gasoline-tank, (not shown,) and a starting cup or cell c^7 , tapped by a passage 60 c^8 , leading to the outlet or delivery section of the discharge-passage c^5 from the head c^4 of the feed-cup 24. Said passage c^8 from the starting cup or cell c^7 is normally closed by a hand-valve 27. The inlet-pipe section c^3 of 65 the feed-cup is shown as plugged or closed at its upper end, but as provided with lateral discharge-openings near its top. The overflow-pipe section c^6 , receiving from its open 70 upper end, determines the height of the oil-level which is maintained within the feed-cup. The discharge-passage c^5 within the discharge-head c^4 receives the oil from a point below the oil-level in the cup, preferably 75 from near the bottom of the cup, as shown in Fig. 6, and then rises, as shown, within the cup itself to a point above the oil-level in the cup and is subject to a needle-valve 28, seated in the head c^4 , and passes thence downward and outward, as shown, through 80 the projecting and screw-threaded end of the discharge-head c^4 . As shown, the needle-valve 28 has screw-threaded engagement with an internal thread formed in the reduced upper end portion of the discharge-head c^4 . 85 The needle-valve 28 is provided with an air-inlet duct f for a purpose which will presently appear. The reduced upper end portion of the discharge-head c^4 is screw-threaded on its exterior and is tapped through the cap 90 of the cup and engaged by a draw-nut c^9 as a convenient means for clamping together the ends and the body of the cup. The needle-valve 28 is also screw-threaded on its exterior and is engaged by a set-nut 29 for locking 95 the valve in whatever position it may be set. The lower end projecting portion of the discharge-head c^4 being screw-threaded, as

shown, affords a convenient means for applying the cup directly to the top of the intake-valve casing, as best shown in Fig. 3.

With this construction and disposition of the parts of the feed-cup the action thereof is as follows: The gasoline or other oil is supplied from the pump or other source to the feed-cup through the inlet-pipe section c^3 and will accumulate therein to the level of the overflow-pipe section c^6 . The oil is drawn from the feed-cup under the suction action from the engine-piston when making the suction-stroke. The oil having been started through the passage c^5 by the suction-stroke of the engine-piston would continue to flow after the piston had completed its suction-stroke on the siphon principle, owing to the relative levels of the feed-cup and the point of discharge to the commingling-chamber of the engine, were it not for the presence of the air-duct f in the needle-valve 28. This air-duct f in the needle-valve 28 affords a supply of air to the oil-feed passage c^5 , thereby preventing the establishment of any siphon action in the delivery-passage from the feed-cup, and also serving the further important function of introducing a small jet or current of air at the axial center of the moving column of oil within the discharge-section of the delivery-passage c^5 from the feed-cup. Hence more or less air will be commingled with the oil before it reaches the commingling-chamber or main air-supply pipe of the engine. At the point of delivery to the main air-supply pipe the inmoving column of oil contains a jet of air at its center or axis and is then enveloped on its exterior by the inrushing body of air from the air-supply pipe 23, thus insuring a most thorough commingling of the air and the oil before reaching the intake-valve 8. The starting cup or cell c^7 is of less height than the overflow-pipe section c^6 , and hence when the engine is running the starting-cell will constantly be full of oil. As the feed-cup stands above the level of the commingling-chamber in the intake-valve casing, it is of course obvious that the oil will flow by gravity from the starting cup or cell c^7 whenever so desired. To obtain a starting charge of oil, it is therefore only necessary to open the passage c^8 from the starting-cup c^7 by manipulating the hand-valve 27. This is a great convenience, as it enables the engine to be started very quickly. In order that the starting charge may feed from the cell c^7 within the feed-cup 24 by gravity, as is desirable for quick starting, it follows that the feed-cup 24 must be above the level of the point of discharge of the oil within the commingling-chamber of the engine. It follows that the delivery-passage c^5 for the normal oil-feed from the feed-cup 24 must at some point between the inlet thereto and the discharge therefrom rise above the liquid-level within the feed-cup, or otherwise the cup would empty by gravity. As shown, the delivery or feed passage c^5 from the feed-cup rises

above the oil-level of the cup within the cup itself. The rise, however, might be outside the cup if a suitable pipe were employed. It is convenient that the duct c^8 from the starting-cell should tap the main or normal feed-passage c^5 from the cup. With that construction it follows that the point of discharge into the commingling-chamber must be below the liquid-level of the cup in order to permit the starting charge from the cell c^7 to flow by gravity therethrough. Hence a siphon action would necessarily follow were it not for the presence of the supply of air to the said delivery-passage c^5 through the duct f of the needle-valve 28 or other means provided for that purpose. Of course the air-supply to the said feed-passage c^5 might be otherwise obtained than through the controlling-valve 28, so far as preventing the siphon action is concerned. The needle-valve 28 might also be applied to the delivery-passage c^5 from the feed-cup at any other convenient point, and nevertheless be provided with the open air-duct f , as long as the top of the duct f was above the oil-level in the cup. The construction illustrated is, however, the most convenient. The feed-cup as thus constructed is also extremely simple and cheaply made. Without the air-inlet to the delivery-passage from the feed-cup I found by experience that an excessive feed of oil occurred under the siphon action after the suction-stroke of the piston had ended. This greatly interfered with the best action of the engine and also wasted oil. This provision of means for breaking the siphon or preventing any siphon action from the feed-cup is one of the most important features of my invention. The gravity-feed starting-cell c^7 is another.

It will be understood that the details of my invention may be changed without departing from the spirit thereof.

What I claim, and desire to secure by Letters Patent of the United States, is as follows:

1. A feed-cup for explosive-engines, having an inlet for receiving the gasoline or other hydrocarbon, from the pump or other source, an overflow-outlet from a point above the bottom of the cup, a discharge or engine-feed passage which, at some point between its receiving and delivery ends, rises above the liquid-level in the cup and delivers to the engine below the bottom of said cup, and which discharge-passage is provided with an air-inlet, whereby any siphon action from said passage is prevented and a portion of air enters with the hydrocarbon oil, substantially as described.

2. A feed-cup for explosive-engines having an inlet for receiving the gasoline or other hydrocarbon oil from the pump or other source, an overflow-outlet from a point above the bottom of the cup, a discharge or engine-feed passage, which, at some point between its receiving and delivery ends, rises above the liquid-level in the cup and delivers to the engine, below the bottom of said cup, and a

needle-valve seated in said discharge-passage, for controlling the same, and provided with an axial air-inlet duct, substantially as and for the purposes set forth.

5 3. In an explosive-engine, the combination with the normal feed devices for the gas or oil, of a gravity-feed starting cell or cup normally charged from said main feed devices and provided with a hand-valve, substantially as and for the purposes set forth.

4. A feed-cup for explosive-engines, having an inlet for the oil or gas, an overflow-outlet from a point above the bottom of the cup, a discharge-passage for the normal feed to

15 the engine, and a starting cell or cup below the oil-level within said main feed-cup, and equipped with a hand-valve controlling the delivery-passage therefrom, substantially as and for the purposes set forth.

5. The feed-cup 24, having the oil or gas 20 inlet c^3 , the overflow-outlet c^6 , the discharge-head c^4 provided with the discharge-passage c^5 rising from below to a point above the liquid-level in the cup, the needle-valve seated in said head for controlling said normal feed- 25 passage, and having the air-inlet as described, and the starting-cup c^7 submerged within the main cup 24 and having the valve discharge-passage tapping the main feed-passage from the cup, substantially as and for the pur- 30 poses set forth.

In testimony whereof I affix my signature in presence of two witnesses.

EMIL WESTMAN.
